UNITED STATES PATENT OFFICE

103,414

DESIGN FOR A PINKING TRIMMER OR SIMILAR ARTICLE

Victor J. Sigoda, Brooklyn, N. Y.

Application March 25, 1936, Serial No. 61,774

Term of patent 14 years

To all whom it may concern:

Be it known that I, Victor J. Sigoda, a citizen of the United States and a resident of Brooklyn, in the County of Kings and State of New York, have invented a new, original, and ornamental Design for Pinking Trimmer or Similar Article, of which the following is a specification, reference being had to the accompanying drawing, forming part thereof:—

Figure 1 is a top plan view of a pinking trimmer or similar article embodying my new design. It is to be understood that the portion shown in full lines is continued throughout the portion shown in broken lines.

Figure 2 is an edge view thereof; and

Figure 3 represents an internal edge view taken on the line 3—3 of Fig. 1.

The characteristic features of my design reside in the facets on the side of the pinking trimmer or similar article which meet the usual cutting teeth arranged around the peripheral edge of the article, as seen in Figure 2, and in the series of scallops around the inner boundary of the facets, as seen in Figures 1 and 3.

I claim:—

The ornamental design for a pinking trimmer or similar article, substantially as shown, and described.

VICTOR J. SIGODA.
